UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

SHOE-PRESSING MACHINE.

Application filed April 14, 1925, Serial No. 23,051, and in Great Britain April 22, 1924.

This invention relates to shoe pressing machines and is illustrated as embodied in a so-called automatic leveling machine of the type disclosed in United States Letters Patent 5 No. 1,239,664, granted Sept. 11, 1917, on the application of W. C. Baxter, although the invention in various aspects is not limited to embodiment in machines of this type.

In leveling machines of this type, the shoe 10 is supported on a last which rests on a jack comprising a heel post and a toe post or support, and is held firmly thereon by appropriate mechanism. These supports as a whole are adjustable to fit the shoe being 15 treated and the jack is rocked back and forth under a leveling roll which exerts a heavy pressure on the shoe.

It has been found in leveling shoes on 20 jointed lasts having relatively movable heel and fore parts, such as hinge lasts, that the bonding mechanism between the last parts is sometimes too weak to take the pressure of the leveling tool and that consequently the pressure sometimes distorts or breaks the 25 last, thus causing damage to the shoe being treated.

It is a principal object of the present invention to prevent such damage, and to this 30 end the invention provides an improved shoe-pressing or leveling machine organization including a support for the last in the neighborhood of the joint between the heel end and the forepart. Preferably this support will be in addition to the heel and forepart (or toe) 35 supporting mechanisms heretofore characteristic of leveling machines. In the embodiment shown, the supporting mechanism comprises a finger arranged to enter a cut or depression between the last parts, to support the 40 last.

In another aspect, the invention provides 45 supporting means for a last between its ends constructed and arranged to be automatically positioned and locked in last-supporting position, which, although generally applicable to pressing or leveling machine organizations of various types, is very well adapted for use in an automatic roll leveling machine of the type above referred to. Preferably, and 50 in accordance with a further feature of the invention, the support for the intermediate or joint portion of the last automatically measures the distance from its contact point with the last to a member or abutment to

which the pressure imparted by the leveling 55 element to the last is transmitted, thus avoiding the necessity of adjustment for different styles and sizes of lasts. Conveniently, and in the disclosed embodiment of the invention, the result above stated is accomplished 60 by an organization in which the finger above referred to is resiliently forced upwardly to meet the last, and in which the lower end of the finger is supported through a cam which cooperates with it in varying relations, de- 65 pending on the contour and dimensions of the last. Preferably, also, the cooperation of this cam with the finger is automatic and is controlled by the operations of jacking and unjacking the shoe (or last) so that the 70 operator needs to devote no attention whatever to the supporting means.

Another feature of the invention consists 75 in a novel construction whereby the last supporting means is rendered adjustable to contact with the last in the desired locality, considered longitudinally of the last. In the illustrated machine which is adapted especially for the treatment of shoes on hinge lasts of the type having a V cut in their upper 80 surfaces to permit the hinging collapse, the desired result is attained by pivoting the contact member for longitudinal movement relatively to the last, so that it automatically slides into the V to seat itself in position 85 to support the last in the region of its joint or hinge.

These and other features of the invention comprising certain novel combinations and arrangements of parts will be understood 90 from the following description of a preferred embodiment thereof selected for purposes of illustration and shown in the accompanying drawings, in which,

Fig. 1 is a side elevation of the front portion of a machine of the type referred to. 95

Fig. 2 is a perspective view of the jack mechanism as seen from the right side.

Fig. 3 is a somewhat enlarged view of the twin mechanism on the other side of the machine as seen from the left side. 100

The illustrated jack mechanism in various respects is identical with that shown in the Letters Patent referred to and reference may be had to said Letters Patent for a more 105 complete disclosure of the construction and operation of parts not fully described herein. The jack as a whole is oscillated under a

leveling roll 10 about the axis of a rock-shaft 12, on which it is mounted, by power-operated mechanism which need not be described in detail since it is fully disclosed in the above-mentioned Letters Patent. The roll is supported in a fork 11 which is hinged at its rear end and forced down toward the jack by heavy springs. The oscillation of the jack follows a cam-controlled cycle, and the jack is automatically thrown out to unjacking and jacking position at the end of the cycle, all of which will be clear by reference to the patent. The jack consists essentially of a toe post 14 mounted on the shaft 12, and a heel post 16 which is pivoted at 18 to a crank-arm 20 depending from the toe post. The relative adjustment of the two posts is effected by a hand-screw 22, extending between the heel post and a lug on the hub of the toe post. The jack pin 24 is tilted away from the operator by a rod 26 operated by gearing 28 and a wrench-receiving head at 30. The shoe is jacked by placing the jack-pin hole of its last on the jack pin 24, adjusting the screw 22 until the toe of the shoe falls properly into the toe rest 32, and turning the head 30 until the tilting of the jack pin forces the toe of the shoe firmly into the toe rest. All of this mechanism is substantially as shown in the patent referred to.

Pivoted on the heel post 16, and conveniently on the shaft 34 of one of the gears 28, is a cam or locking member 36, having a downwardly extending tail 38. A swinging lever 40 is pivoted at 42 at the bottom of the heel post and has a lug 44, arranged to be engaged by the cam 36, which swings around its pivot to contact with the lug in any position which the latter may assume. When the jack is swung out and down toward the operator to jack or unjack a shoe as shown in Fig. 3, a fixed bracket 46 on the machine frame contacts with the tail 38 and prevents the cam 36 from following the lug 44, thus stressing a spring 48 which tends to throw the cam on to the lug. The lever 40 is then free to swing in either direction about its pivot 42. The lever 40 is U-shaped and embraces the lower end of the heel post.

On the other end of the lever 40 at 50 there is pivoted to the lever the lower end of a rod 52, which slides lengthwise in a guide 54, and is resiliently held in raised position by a spring 56 attached to a lug on the rod at its lower end. Pivoted at 58 to the upper end of the rod 52 is a last contacting finger 60, having a spring-pressed pin 62 in it which engages a V cut in a lug 63 at the upper end of the rod 52 as shown in Fig. 3, to hold the finger resiliently in a mean or standard position.

The machine being in the condition shown in Fig. 3, the operator puts the shoe on the jack as described above, and the finger 60 contacts with the last. The last shown has

a V cut at its hinge joint and the finger automatically enters it and settles to the bottom of it, rotating about the pivot 58 if necessary. In case the same type of last is to be used exclusively on the machine, the finger will conveniently be made to fit the last in any desirable manner. As shown, the finger, by reason of its pivotal mounting at 58, is adapted to cooperate efficiently with any last with a V cut. As the last settles down on the jack pin, the finger 60 and the rod 52 are forced down against the spring 56 carrying the lever 40 with them, (the cam 36 being inoperative, as already explained) until the shoe is in proper position on the pin. The operator will then swing the heel post toward the toe post, if such adjustment is required by the length of the shoe, and will lock the shoe in the jack. When the machine is started and the jack starts to swing up under the roll 10, as shown in Fig. 2, the tail 38 leaves the bracket 46 and the spring 48 pulls the cam 36 against the lug 44, thus locking firmly the lever 40, rod 52 and finger 60 against downward movement under the leveling pressure, and the joint of the last is thus supported firmly against the pressure of the leveling roll, so that damage to the last and consequently to the shoe is prevented. The shaft 34 constitutes an abutment which takes the pressure transmitted from the last through the rod, lever and cam. It will be clear that this mechanism comprising provision for a variable operative relation between the cam 36 and the lug 44 constitutes in effect a measuring means for the distance between the last and the abutment, or a take-up mechanism between these parts.

It will be clear that the operation of the illustrated supporting device is entirely automatic. It unlocks when the jack swings out to interchange shoes and locks as it swings back to operative position and requires no attention whatever from the operator.

Having thus described my invention, what I claim as new and desire to secure by Letters Patent of the United States is:—

1. In a shoe pressing machine, a pressing tool, a last heel support, a last forepart support, and additional means for supporting a jointed last between said supports in the neighborhood of the joint between its heel and fore parts, said additional means being adjustable to effect operative contact with the last in a location between its opposite sides irrespective of the position of the last heightwise on said supports.

2. In a shoe pressing machine, a pressing member and power means for operating it, a last heel support, a last forepart support, and additional means for supporting a hinged last between said supports in the neighborhood of the hinge between its heel and fore parts, said additional means comprising a rod

arranged to extend upwardly under the last and a last supporting member pivotally mounted on the upper end of said rod.

3. In a shoe pressing machine, a pressing member, a last toe support, a last heel support and power mechanism for relatively moving the supports and member, and additional supporting means movable to conform to the position of the last in a location between the two first-named supports and automatically locked in position to support the last against pressure of the pressing member on its bottom face after the shoe on the last has been placed in position on the said supports.
- 15 4. In a shoe pressing machine, a pressing instrumentality, a last toe support, a last heel support and power mechanism for relatively moving the supports and instrumentality, and additional supporting means constructed and arranged to contact with the last between the two said supports when the last is placed thereon, to be displaced resiliently as the last is moved to operative position on the supports and to be locked in last supporting position 25 after the last has been moved to present a shoe thereon in operative relation to the pressing instrumentality.

5. In a shoe pressing machine, a pressing member, last supporting means, and additional supporting means movable to conform to the position of the last in a location between the ends of the last and automatically locked in position to support the last against pressure of the pressing member on its bottom face 35 after the shoe on the last has been placed in operative position on the first said supporting means, the additional supporting means being also movable longitudinally of the last to support the last in the desired locality thereof irrespective of the size and style of the last.

6. In a shoe pressing machine, a power-operated pressing member, means for supporting a two-part jointed last, and additional supporting means movable to contact with the last between its ends and automatically locked in last supporting position after the shoe on the last has been placed in position on the first said supporting means, the additional supporting means being also automatically and 45 resiliently movable longitudinally of the last to seat itself in a depression in the upper surface thereof at the joint between the last toe and heel parts.

7. In a shoe leveling machine, a leveling roll, a jack arranged to support a last at its ends to hold it under the roll for treatment of a shoe on the last and to be thrown out of operative position to jack and unjack the last, power means for relatively oscillating the 55 jack and roll, and a supporting means constructed and arranged to support the last between its ends and to be locked in operative supporting position in response to movement of the jack into operative position under the roll.

8. In a shoe leveling machine, a leveling roll, means arranged to support a last at its ends to hold it under the roll for treatment of a shoe on the last and to be thrown out of operative position to insert and remove the last, power means for relatively oscillating the supporting means and roll, and additional supporting means constructed and arranged to contact with the last between its ends and to adjust itself to the position of the last when the first-named supporting means is out of operative position and to be locked in operative supporting position in response to movement of the last into operative position under the roll.

15 9. In a shoe leveling machine, a leveling roll, means arranged to support a last at its ends to hold it under the roll for treatment of a shoe on the last and to be thrown out of operative position to insert and remove the last, a supporting member constructed and arranged to support the last between its ends against pressure of the roll on its bottom face, and a locking member for the supporting member.

20 10. In a shoe leveling machine, a leveling roll, a jack arranged to support a last at its ends to hold it under the roll for treatment of a shoe on the last and to be thrown out of operative position to jack and unjack the last, a supporting member constructed and arranged to support the last between its ends against pressure of the roll on its bottom face and to move with the last as it is placed on the jack, and a locking member for the supporting member.

25 11. In a shoe leveling machine, a leveling roll, means arranged to support a last at its ends to hold it under the roll for treatment of a shoe on the last and to be thrown into and out of operative position in relation to the roll, a supporting member constructed and arranged to support the last between its ends and to move with the last as it is placed on the supporting means, and a locking member for the supporting member controlled by the operation of throwing the supporting means into operative position.

30 12. In a shoe leveling machine, a leveling member, a jack arranged to support a last at its ends to hold it under the leveling member for treatment of a shoe on the last and to be thrown into and out of operative position in relation to the leveling member, a movable supporting member constructed and arranged to support the last between its ends, and a locking member for the supporting member automatically controlled by movements of the jack to and from operative position under the leveling member.

35 13. In a shoe leveling machine, a power-operated leveling roll, a jack arranged to support a last at its ends to hold it under the roll for treatment of a shoe on the last and to be thrown out of operative position to 130

jack and unjack the last, a movable supporting member constructed and arranged to support the last between its ends against pressure of the roll on its bottom face, a part 5 arranged to take the thrust transmitted from the last through the supporting member, and a locking member for said part to hold it in position to sustain the supporting member after the last is jacked.

10 14. In a shoe leveling machine, a leveling member, a jack arranged to support a last at its ends to hold it under the leveling member for treatment of a shoe on the last and to be thrown into and out of operative position 15 in relation to the leveling member, a movable supporting member constructed and arranged to support the last between its ends, a lever arranged to take the thrust transmitted from the last through the supporting 20 member and movable to follow the movements of the supporting member as the last is jacked against it, and a locking member for the lever operated in response to movement of the jack into operative position under the 25 leveling member to hold the lever in position to support the supporting member.

15 15. In a shoe leveling machine, a leveling instrumentality, a jack arranged to support a last at its ends to hold it under said instrumentality for treatment of a shoe on the last and to be thrown into and out of operative position in relation to the leveling instrumentality, a supporting member movable to support the last between its ends, and a locking 30 member for the supporting member arranged to cooperate with it in varying relations dependent upon its relation to the last being supported, said locking member being arranged to be moved into locking position 35 as an incident of the operation of moving the jack into operative position relatively to the leveling instrumentality.

40 16. In a shoe leveling machine, a leveling roll, a jack arranged to support a last at its ends to hold it under the roll for treatment 45 of a shoe on the last and to be thrown out of operative position to jack and unjack the last, a supporting member constructed and arranged to support the last between its ends, 50 and a locking member for the supporting member pivoted on the jack and arranged to hold the supporting member firmly in position to support the last when in operative 55 position and to be swung out of operative position when the jack is moved from operative position relatively to the roll.

60 17. In a shoe leveling machine, a leveling roll, a jack arranged to support a last at its ends to hold it under the roll for treatment 65 of a shoe on the last and to be thrown out of operative position to jack and unjack the last, a movable supporting member constructed and arranged to contact with the last between its ends and to move with the last as the last 70 is placed on the jack, and a locking member

for the supporting member pivoted on the jack and arranged to hold the supporting member firmly in position in contact with the last when in operative position, said locking member being normally resiliently held in 75 operative relation to the supporting member and having a tail arranged to be engaged when the jack is moved to inoperative position and thereby swing the locking member out of operative relation to the supporting 80 member to permit the supporting member to move with the next last as the latter is settled into operative position on the jack.

18. In a shoe leveling machine, a leveling roll, a jack arranged to support a hinged last at its ends to hold it under the roll for treatment of a shoe on the last and to be thrown out of operative position to jack and unjack the last, a supporting means arranged to contact with the last in the neighborhood of its hinge and resiliently mounted on the jack to move with the last as the last is placed in jacked position, and a locking member arranged to hold the supporting member firmly under pressure transmitted from the last in 85 the leveling operation and arranged to be moved out of cooperative relation with the supporting member as the jack is moved out of operative position relatively to the roll.

90 19. In a shoe leveling machine, a leveling roll, a jack arranged to support a jointed last at its ends to hold it under the roll for treatment of a shoe on the last and to be thrown out of operative position to jack and unjack the last, a supporting means arranged to contact with the last in the neighborhood of its joint and resiliently mounted on the jack to move with the shoe as the shoe is placed in jacked position, a locking member pivoted on the jack and comprising a cam 95 surface arranged to hold the supporting member firmly under pressure transmitted from the last in the leveling operation and having a tail arranged to be engaged as the jack is moved from operative position relatively to the roll and to be moved thereby out of operative relation to the supporting member, and means for restoring the cam to operative relation with the supporting member when the jack is returned to operative relation with 100 the roll.

110 20. An automatic leveling machine comprising a leveling roll, a jack mounted to swing into and out of operative relation to the roll, power operated mechanism for 115 swinging the jack, and means for supporting a jointed last on the jack in the neighborhood of its joint against the pressure of the roll.

120 21. An automatic leveling machine comprising a leveling roll, a jack, power operated means for relatively operating the roll and jack, and means for supporting a hinge last on the jack in the neighborhood of its hinge 125 movable to contact with the last at the de- 130

sired locality irrespective of its size or style.

22. An automatic leveling machine comprising a leveling roll, a jack, power operated means for relatively operating the roll and

5 jack, means for supporting a last on the jack between its ends, a thrust-taking abutment cooperating with said supporting means, said supporting means being constructed and arranged to measure automatically the distance 10 from the last to the abutment, and means for locking the supporting means in operative position relatively to the abutment after the last is properly jacked.

23. An automatic leveling machine comprising a leveling roll, a jack, power operated means for relatively operating the roll and jack, means for supporting a last on the jack between its ends, a thrust-taking abutment cooperating with said supporting means, said supporting means being constructed and arranged to measure automatically the distance 15 from the last to the abutment, and means for automatically locking the supporting means in operative position relatively to the abutment in response to movement of the last into 20 operative position relatively to the roll.

24. In a shoe pressing machine, a power operated pressing member, last toe and heel supports, a pressure-taking abutment, an additional supporting means movable to contact with the last between the toe and heel supports to support the last against pressure of the pressing member on its bottom face and constructed and arranged automatically to 30 measure the distance from the last to the abutment, and a locking means for holding the additional supporting means in operative 35 relation to the abutment.

25. In a shoe pressing machine, a power operated pressing member, last toe and heel supports, a pressure-taking abutment, an additional supporting means movable to contact with the last between the toe and heel supports and constructed and arranged to 40 measure the distance from the last to the abutment, and a locking means for holding the additional supporting means in operative 45 relation to the abutment, said locking means being automatically moved into inoperative 50 and operative positions incidentally to the finishing and beginning of the leveling operation, respectively.

26. In a shoe pressing machine, pressing means, last supporting means, an additional 55 supporting member for the last resiliently controlled to adjust itself to the position of the last, and means for holding the additional member positively in operative supporting position.

27. In a shoe pressing machine, pressing means, last forepart and heel supporting means, an additional supporting member for the mid portion of a jointed last resiliently 60 controlled to seat itself in the joint of the last, and means for holding the additional member

positively in operative supporting position.

28. In a shoe pressing machine, pressing means, last supporting means, an additional supporting member for the last resiliently controlled to adapt itself to the position of the last, and automatic means for locking the additional member in operative supporting 70 position.

29. In a shoe pressing machine, a pressing member, supporting members arranged to support the last at its ends and to hold it under the pressing member for treatment of a shoe on the last, and additional supporting means movable to conform to the position of the last in a location between the two supporting members and automatically locked in position to support the last against pressure on its bottom face after the shoe on the last has been placed in position on the said supporting members.

30. In a shoe pressing machine, a pressing member, means for supporting a last having a V-shaped hinge-cut in its upper surface, and additional supporting means constructed and arranged to seat itself automatically in 80 said cut to support the last under the pressure of the pressing member.

31. In a shoe pressing machine, a pressing member, means for supporting a last having a concavity in its upper surface against pressure of the pressing member on its bottom surface, additional supporting means constructed and arranged to seat itself resiliently in 90 said concavity to support the last against the pressure of the pressing member, and means for locking the additional supporting means.

32. In a shoe pressing machine, a pressing member, means for supporting a last having a concavity in its upper surface against pressure of the pressing member on its bottom surface, additional supporting means constructed and arranged to seat itself resiliently in 100 said concavity to support the last against the pressure of the pressing member, and means for automatically locking the additional supporting means before the last is moved into operative relation to the pressing member.

33. In a shoe pressing machine, pressing means, last supporting means arranged to support a last having a V-shaped hinge-cut, and additional supporting means comprising a pivoted finger constructed and arranged to seat itself in the said cut.

34. In a shoe pressing machine, pressing means, last supporting means arranged to support a last, additional supporting means comprising a pivoted finger constructed and arranged resiliently to seat itself in contact with the upper surface of the last to support it against pressure of the pressing means on its bottom surface, and means for locking the finger in operative position.

35. In a shoe pressing machine, the combination with means for applying pressure to 130

the bottom of a shoe on a last, of means for supporting the last at its opposite ends, additional means for supporting the last between its ends against pressure on its bottom face, 5 said additional means being movably mounted to adjust itself to the last, and means for locking said additional supporting means in the position determined by the last.

36. In a shoe pressing machine, the combination with means for applying pressure to the bottom of a shoe on a last, of means for supporting the last at its opposite ends, additional means for supporting the last between its ends against pressure on its bottom face, 10 said additional means being yieldingly movable heightwise of the last in response to pressure of the last thereon to adjust itself variably to different lasts, and automatic means for locking said additional supporting 15 means against further movement in the same direction from the position determined by the last.

37. In a shoe pressing machine, the combination with means for applying pressure to the bottom of a shoe on a jointed last, of means 20 for supporting the ends of the last, additional supporting means comprising a member movable both heightwise and lengthwise of the last to seat itself in the joint of the last and to

assume different positions in accordance with 30 the shapes of different lasts, and means for supporting said member positively against pressure on the bottom face of the last in the position assumed by said member under control of the last. 35

38. In a shoe pressing machine, the combination with pressing means, and a jack movable into and out of operative relation to said pressing means and constructed to support a last at its opposite ends, of additional means 40 carried by the jack for supporting the last between its ends against pressure of the pressing means on its bottom face, said additional means being arranged to assume different positions under the control of different lasts, 45 and automatic means controlled by movement of the jack to lock said additional supporting means in the position determined by the last.

39. In a shoe pressing machine, the combination with means for applying pressure to the bottom of a shoe on a jointed last, of means 50 for supporting the ends of the last, and additional means for engaging the last in the joint to support it against said pressure.

In testimony whereof I have signed my name to this specification.

ERASTUS E. WINKLEY.

CERTIFICATE OF CORRECTION.

Patent No. 1,689,609.

Granted October 30, 1928, to

ERASTUS E. WINKLEY.

It is hereby certified that error appears in the printed specification of the above numbered patent requiring correction as follows: Page 4, line 74, claim 17, strike out the words "and thereby" and insert instead the word "to", and line 76, strike out the word "to" and insert the words "and thereby"; and that the said Letters Patent should be read with these corrections therein that the same may conform to the record of the case in the Patent Office.

Signed and sealed this 10th day of September, A. D. 1929.

(Seal)

M. J. Moore,
Acting Commissioner of Patents.
